UNITED STATES PATENT OFFICE

2,541,315

COMBUSTION CHAMBER STRUCTURE FOR
FLUID FUEL BURNING AIR-HEATING FUR-
NACESThomas J. West, Wilkinsburg, Pa., assignor of
forty per cent to Ellsworth L. Riling, Wilkins-
burg, Pa.

Application July 3, 1946, Serial No. 681,220

5 Claims. (Cl. 126—116)

1

This invention relates to furnaces or air heaters, and more particularly to a fuel gas burning, combustion control, air heating and distribution unit for such apparatus. It has for one of its objects to improve generally upon such apparatus.

Another object is to produce a simple yet practical and highly efficient, unitary fuel gas burner and control assembly capable of being applied to an ordinary hard fuel burning furnace or air heater of conventional type and necessitating merely the removal of the grate element or elements and other readily removable parts so as to establish free open communication between the fire pot or box and the ash pit or chamber therebeneath, and at the same time minimizing other, if any, alterations or changes in the structure of the furnace or heater itself.

A further object is to provide for contractible and expansible adjustment of a part of the unitary assembly which is inserted in the fire box of the furnace or air heater so that the unit is applicable to furnaces or heaters having fire pots of different sizes, particularly as to diameter, such as for example, those varying from 14 to 28 inches in diameter or in other varying proportions.

Still another object is to attain a more practical and thorough combustion of the fuel gas and a more effective heating of air and better working distribution of the same.

Other objects and advantages to be attained will hereinafter more fully appear in the following description.

Practical but non-limiting embodiments of the invention are exemplified in the accompanying drawings, in which:

Figure 1 is a vertical sectional and elevational view illustrating one working adaptation of the invention;

Figure 2 is a view mainly in top plan and in partial section on the line 2—2 of Figure 1;

Figure 3 is a detail plan view of one of the segmental members or butterfly plates of the dished or upwardly flared, annular baffle or partition element of the unitary assembly;

Figure 4 is a fragmentary detail plan view of the head cover plate of the burner cabinet or chest box of the unit;

Figure 5 is a sectional view of an air heating apparatus in which there is a modified adaptation of the invention;

Figure 6 is a section on the line 6—6 of Figure 5;

Figure 7 is a section taken on or about the line 7—7 of Figure 2, illustrating one manner of as-

2

sembling the segmental members or butterfly plates of the annular baffle or partition; and

Figure 8 is a view similar to Figure 7 but showing a modified assembly arrangement of the segmental members or butterfly plates.

Figure 9 is a perspective view of the unit shown in Figures 1 to 4.

Referring now first more particularly to Figures 1 through 4, and 7 and 8, the numeral 10 designates the lower portion of the shell or casing of a conventional furnace or heater. This casing or shell 10 may be that of a gas fired type, usually cylindrical in horizontal cross section and hollow and plain relatively smooth walled throughout, or, if it be of a hard fuel (such as coal) type, the grate element or elements usually provided below the fire pot or box and between the latter and the ash pit or box is or are removed, leaving a freely open and uninterrupted communication between the fire box and the ash pit.

The unitary assembly of the present invention has its inner or head end portion located in the lower part of the furnace or heater so that combustion of fuel takes place effectively within the normal fire pot portion of the furnace or heater, and the cabinet or chest box portion proper of the unit is projected outside the furnace or heater through the usual door opening of the ash pit or box portion thereof. That is to say, communication between the ash pit or box and the fire pot or box is uninterrupted except as to a specially provided annular baffle or partition element on the head end portion of the cabinet or chest box of the unit which is located within the casing or shell 10 of the furnace or heater.

The unit of the present invention, as shown, comprises an elongated, rectangular, horizontal cabinet or chest box 11, the head or inner end portion 12 of which is located within the lower or base portion of the furnace or heater shell 10 (see Figure 1). A cover plate 13 is provided on the head or inner end portion 12 of the cabinet or chest box 11 within the furnace or heater shell, and, preferably, additional cover plates 14 and 15 are provided on the cabinet or chest box outside the furnace or heater shell. These cover plates 13, 14 and 15 are made detachable, removable and replaceable, at will, in any desirable or approved manner (not shown in detail) so that access can be had to the interior of the cabinet or chest box when necessary.

The cover plate 13 at the inner or head end of the cabinet or chest box 11 is provided with a circular opening 16 surrounded by an upstanding annular flange or collar 17. This opening 16 is

of substantial diameter and projected upwardly and axially therethrough is a conventional gas burner head 18 (see Figures 2 and 9).

The burner head 18 may be of any suitable type and as the same, of itself alone, is not of the essence of the invention, there is no detail illustration thereof in the drawings. Suffice it to say that the burner element 18 is connected by an elbow coupling 19 to a conventional burner gun 20, which latter is supported on the bottom of the cabinet or chest box 11 by a bracket element 21, said burner gun 20, as thus supported, in turn supporting the burner head 18. The flared outer end portion 22 of the burner gun 20 is provided with the usual adjustable air inlet openings 20a and communicating axially with said gun 20 is a gas supply pipe or nipple 23. This pipe 23 has incorporated therein a controlling cut-off or throttle valve 24.

The regulated supply of fuel gas is taken centrally into the burner gun 20 where it is mixed in the usual manner with air taken into the gun through the apertured flared end thereof, whence the thus created combustible mixture is delivered through the elbow coupling 19 to the burner element proper 18, where it is ignited by means such as a pilot burner 25, the details of which will be described later on.

Surrounding the circular flange 17 of the head cover plate 13 is an annular series of relatively small rectangular apertures 26 in said plate (see Figure 4). These apertures 26 are provided to receive, with a limited freely swingable and comparatively tight fit therein, relatively small lug extensions 27 formed at the smaller inner ends of segmental, substantially fan-shaped members or sectors 28, which latter, when assembled in radial and marginally meeting cooperative relation, form an annular dished or upwardly flared baffle or partition (see Figures 2 and 9) supported on the head plate 13, closely surrounding the circular flange 17 of the plate at the inner ends of said members 28, with the outer ends of said members 28 resting in close contact with the inner face of the annular wall of the furnace or heater casing or shell 10.

The form, arrangement, adjustability and conformability of the dished or upwardly flared baffle or partition produced by the assembly of said segmental sector-shaped members 28 is an important and essential feature of the present invention. This baffle or partition not only closes communication annularly of the aforesaid burner opening 16 at the head end of the unitary fuel and combustion control assembly of the invention, between the lower or base space of the furnace or heater and the combustion chamber thereabove, but the same is contractibly and expansibly adjustable to fit and be placed workably in furnace or heater casings or shells of different interior diameters to form substantially the bottom of the combustion chamber.

The respective segmental or fan-shape plate-like members 28 may be made in sets, each member of a predetermined standard size. In assembling the members 28 to produce the dished or upwardly flared baffle or partition, the lug extensions 27 of the members, as just above noted, although fitted comparatively tightly in the annular series of apertures 26 of the head plate 13, do have considerable freedom of movement to permit much variable up and down swinging movement of said members 28 so that the partition assembly is adjustably conformable to the interior diameters of various dimensions inside 75

the furnace casing or shell 10, as previously above described.

In the assembly, the segmental plates 28 are made to overlap more or less at their radial margins (see Figures 7 and 8). That is to say, the members 28 may be placed in slightly inclined overlapping relation to each other, as illustrated in Figure 7, or the members may be alternately placed in offset parallel planes as shown in Figure 8. In either case, the members are usually made to overlap to an appreciable extent along their radial margins, which overlap, of course, will vary when the members 28 are applied in a baffle or partition assembly in furnaces or heaters of different fire pot or box diameters. So, too, it is obvious that the set of members 28 may be made of a predetermined unitary or standard size to fit a certain size of fire pot or box in some cases and in which event the members may meet in closely abutting radial marginal contact instead of overlapping.

It is further noted that the angularity of dip in the dished effect of the produced annular baffle or partition will vary somewhat in the installation in fire pots or boxes of different diameters where a set of certain standard sized members 28 are used. So, too, the meeting edges of the members 28, whether overlapped or just marginally abutted, may or may not be cemented, welded or otherwise suitably fastened to each other after being assembled in their working position, as illustrated in Figures 1, 2, 7 and 8. Moreover, in some cases, the entire baffle or partition assembly, especially if the members 28 are made of relatively thin metal, may be entirely coated with a suitable cement or an approved refractory material. So, too, it is noted that the plate-like members 28, instead of being made of metal, the same may be molded or otherwise formed of a suitable refractory or fire resistant material.

Supported at a working distance above the burner element 18, by uprights 29, is a horizontally disposed flame spreader 30 having a flat circular top and a convex underside (see Figure 1). The flame spreader 30 itself and the uprights 29 are obviously made of fire resistant material, either entirely of such material or else of metal and covered protectively with such material.

The upper part of the furnace or heater 10 above the aforesaid baffle or partition and the flame spreader may be of any desired or conventional form. Suffice it to say, that this upper part of the furnace or heater is obviously provided with an outlet for the products of combustion (not shown).

As shown more clearly in Figures 1 and 9, the unitary combustion and fuel control assembly of the present invention includes, in addition to the several aforesaid parts, certain correlated, associated and cooperative parts, all contained within the cabinet or chest box 11 and to be now described.

Communicably attached to the outer end of the gas supply pipe or nipple 23 is a conventional electrically operated and controlled valve 31, preferably of the solenoid type and the same, of itself, not being of the present invention, no detailed illustration thereof appears in the accompanying drawings. This valve 31 is operatively connected by a wire line 32 to a suitable electrical transformer or other suitable source of electrical source of electricity 33.

Leading into the electrical valve 31 is a gas

supply pipe or nipple 34 from a conventional gas regulator 35, and leading into the regulator 35 is a gas supply pipe 36 from an outside supply pipe 37, the latter leading from a source of gas supply (not shown).

By the foregoing, it is apparent that a regulated and controlled supply of fuel gas is directed into the burner gun 20, which latter, of itself, is of any suitable conventional type and receives through suitably provided air inlets 29a a regulated and controlled amount of air which is mixed with fuel gas within the element 20 and the produced combustible mixture is delivered to the burner head proper 18, whence the fuel is ignited by means associated with the burner head 18, as will be presently described more fully.

It is here noted that any suitable provision may be made for admitting and controlling a supply of outside air to the cabinet or chest box 11. As shown, suitable louvers or inlet openings 38 are provided in the outer end wall of the cabinet or chest box 11. An opening, having an openable and closable door 39, may also be provided in one or more of the top cover plates 14 or 15 of the cabinet or chest box, as indicated in Figures 1 and 2. It is further obvious that other suitable air intake and control openings may be otherwise and elsewhere provided in the cabinet or chest box 11.

Ignition of the fuel mixture at the burner head 18 may be accomplished by any approved means and in any suitable manner. However, for exemplification, a conventional pilot burner 25, as hereinbefore mentioned, may be provided as illustrated more or less schematically in Figures 1 and 2. This element 25 is supplied with gas through a small-diameter by-pass pipe 40 coupled as at 41 to a conventional valve 42 at a lateral outlet from the electrical gas control valve 31 (see Figure 1). This pilot burner 25 may be lighted so as to burn continuously with a small flame, possibly with automatic control provision for varying the intensity of its flame from time to time during operation of the burner element proper 18, or provision may be made for lighting the pilot burner only at the time of starting ignition of the fuel from the burner head proper 18. So, too, as far as the present invention is concerned, an electrical or other suitable sparking device may be obviously provided for igniting the fuel gas at the burner element proper instead of using a pilot burner.

For mere exemplification of an operative arrangement, there is illustrated more or less schematically an electrical control unit 43 having a suitable wire connection 44 with the transformer or electrical source of supply 33. A conventional operative and control connection 45 is provided between the control unit 43 and the pilot burner 25 (see Figure 1).

From the foregoing explanation, it is apparent that a unitary fuel gas supply and combustion control assembly is produced which is not only practical and efficient for installation and use originally in a furnace or air heater of a specially designed structure, but it is also readily installed in any conventional furnace or air heater, even one previously provided and adapted for the burning of hard fuel such as coal and the like, in which latter cases it is only necessary to remove the grate element or elements and other readily removable parts of the furnace or heater between the fire pot or box and the ash pit or box, and that, after installation, the unitary as-

sembly of the present invention is easily operated and controlled and its operation is carried on economically as well as with a high degree of efficiency and utility.

Not only does the construction and arrangement of the unitary assembly of the present invention lend itself to the ease and speed of installation and removal from the furnace, but the baffle partition retains the generated heat in the combustion chamber, and at the same time free circulation of air is allowed in the ash pit area, the tendency of which is to keep all elements in the cabinet or chest box at a lower heat level and thus promote longevity of the entire unit.

In Figures 5 and 6, a modified exemplification of the invention is illustrated. In this modification, a special type of air heating apparatus is disclosed. As shown, the apparatus comprises a hollow housing or shell 46 containing a major heating chamber 47 and a separate smaller air intake and supply chamber 48.

Within the chamber 47 is a furnace and air heater combination 49. This unit 49, as shown, comprises an upright, generally cylindrical, inner shell 50 having a rounded crowned top wall 51 and a tapered and contracted lower portion 52 with a depending annular collar or flange 53 which rests upon and is secured supportedly and steadily on the top plate or wall of a cabinet or chest box 11 of a unitary gas supply and combustion assembly substantially identical with that hereinbefore described except as to the said annular baffle or partition element including the parts 28. In this modification is included the burner head 18, burner gun 20, cut-off or throttle valve 24, electrical valve 31, gas regulator 35 and the gas supply pipe 37, all of which parts are indicated schematically in Figure 5. Certain obvious other parts are not shown in Figure 5.

In this particular modification, the flame spreader 30, as supported by the uprights 29 on the inner or head end portion 12 of the cabinet or chest box 11, is projected above the burner element 18 and to a horizontal plane just approximately adjacent to that where the cylindrical wall 50 of the furnace and heater unit 49 begins to taper downwardly as at 52. The spreader 30 thus spreads the flame from the burner element 18 annularly, thereby thoroughly heating the cylindrical wall 50. The products of combustion created in the upper chamber portion 54 are discharged and conducted off through the outlet pipe 55, which latter may or may not be provided with a valve or damper 56, as desired.

The cylindrical furnace or air heater shell 50 is formed by the inner juxtaposed sides of an annular series of vertical tubes 57 open at their top ends, as at 58, and at their bottom ends, as at 59. These tubes 57 are made of metal or material of high heat conductivity and they are welded or otherwise integrally held together. The provision and arrangement of said tubes 57 is such that the same become heated from the heat developed within the combustion chamber of the furnace or air heater unit 49, and air from the lower portion of the heating chamber 47 is drawn into the open lower ends of said tubes 57, heated in the tubes to a high degree and discharged from the open upper ends of the tubes.

The tubes 57, in their annular arrangement, are in close contact with each other, and thus afford a greater radiating surface in the passage 75 through the combustion chamber thus formed by

the tubes. This gives a maximum exposed surface to heat the air passing to the exit.

A hot air outlet 60 is provided in the top wall of the heating chamber 47. In the lower part of the division wall 61 between the heating chamber 47 and the cold air intake chamber 48 is a cold air inlet 62.

Communicating with the cold air inlet opening 62 is the discharge nozzle 63 of a conventional blower element 64. This element 64 is driven by a directly associated electrical motor 65, both elements being obvious and merely shown more or less schematically.

Outside air is taken into the cold air chamber 48 through an inlet opening 66 provided in the top wall of the chamber. Located in the cold air chamber 48 between the air inlet opening 66 and the blower 64 is an air filter 67. This filter may be of any conventional form. As shown, it is of a hollow conical form with its apex substantially coincident with the vertical axis of the chamber 48.

In operation of the apparatus shown in Figures 5 and 6, the cold air is drawn into the chamber 48, there filtered, and then blown into the heating chamber 47. The air in the chamber 47 is heated by heat radiated from the combustion chamber 50 and by passing through the tubes 57 before being discharged through the outlet opening 60.

The provision of the annular series of open-ended tubes 57 in the furnace or heater shell 50 is an important and essential feature of the present invention in connection with the fuel gas supply and combustion control elements, in that a more efficient and thorough heating of air is attained with an economical operation of the apparatus.

While the illustrated exemplifications are practical adaptations of the invention, considerable further modifications and changes are contemplated within the spirit and scope of the appended claims. The invention, therefore, is not limited to the specific construction and arrangements shown.

What is claimed is:

1. A furnace comprising a casing, a horizontally disposed closure including a top wall and extending into the lower portion of the casing, said top wall having a central opening in alignment with the center of the casing, a flange on said top wall and surrounding the opening, slots in said top wall and adjacent said flange, an upwardly flared baffle partition surrounding said opening

and flaring upwardly and outwardly with its upper edge in contact with the inner wall of the casing to form a fire box, the baffle partition comprising a plurality of adjoining segmental sector-shaped plates having lugs at their lower ends fitting said slots, a burner head and tip located and supported in the inner end of the closure, the burner tip being centrally disposed in the opening in the closure and extended into the fire box, a flame spreader located co-axially above the burner tip, and cooperative fuel gas and air supply and controlling means for producing an inflammable fuel mixture, all said means being located within the closure.

15 2. A furnace as set forth in claim 1, wherein the sector-shaped baffle plates are of uniform size and overlap at their edges to complete the partition.

20 3. A furnace as set forth in claim 1, wherein the sector-shaped plates adjustably overlap one another at their edges to complete partitions of various diameters and heights.

25 4. A furnace of the type described, comprising a casing, a closure extending into the lower portion of said casing and formed with an opening in its top, said opening being centrally disposed with reference to the casing, the closure top having a series of slots formed around said opening, a series of segmental sector-shaped plates, each 30 plate having a lug at its lower end fitting in one of said slots, the side edges of said plates overlapping and their upper edges engaging the inner wall of the casing to divide said casing and form a fire box, and a burner head and tip centrally disposed in said opening and extending into the fire box.

35 5. A furnace as set forth in claim 4, wherein a flange surrounds the opening in the closure, and wherein the lower edges of the sector-shaped plates engage the flange and the bottom edge of the said plates are supported on the top of the closure.

THOMAS J. WEST.
